CONCRETE-ROADWAY-REINFORCING FABRIC.

1,388,544.

Specification of Letters Patent. Patented Aug. 23, 1921.

Application filed January 10, 1920. Serial No. 350,514.

To all whom it may concern:

Be it known that I, EDWARD L. BENEDICT, a citizen of the United States, residing at Pittsburgh, in the county of Allegheny and State of Pennsylvania, have invented a new and useful Improvement in Concrete-Roadway-Reinforcing Fabric, of which the following is a full, clear, and exact description, reference being had to the accompanying drawings, forming part of this specification, in which:

Figure 1 is a plan view illustrating the manner of laying my improved reinforcing fabric, and

15 Figs. 2 and 3 are plan views showing portions of two different forms of the fabric.

My invention relates to fabric for reinforcing concrete roadways and also to concrete roadways having such fabric embedded therein.

One object of the invention is to provide a fabric of this character which will have a greater weight of metal running transversely of the roadway than longitudinally thereof. This reinforces the roadway in the direction in which the greatest reinforcing strength is required.

Another object of the invention is to provide, if desired, greater reinforcing along the middle portion of the roadway than at its edges.

A further object of my invention is to provide a fabric of this character which is so constructed that it can be readily formed into rolls without the necessity for bending the reinforcing elements in rolling, the fabric being rolled in a direction at substantially right angles to the length of such elements. This not only enables the fabric to be laid as unrolled without the necessity for straightening such elements, but it also permits the use of much lighter stay wires for securing the reinforcing elements, and thus economizes metals in those portions of the fabric which are not effective as reinforced. It also enables the fabric to be unrolled longitudinally of the roadway in the position in which it is to be laid instead of being cut in lengths and laid transversely of the roadway. This feature also effects a considerable saving in the amount of metal required for a given area of roadway, since it reduces to a very large extent the necessity of overlaps, which are required where relatively

narrow strips are laid successively transversely of the roadway.

Referring first to that form of my invention which is shown in Figs. 1 and 2, the numerals 2 and 3 designate the main reinforcing elements in the form of rods, wires or bars of the desired cross-section, and 4 the tie or stay wires. The transverse reinforcing elements are heavier than the longitudinal tie wires. This gives greater reinforcing strength transversely of the roadway than longitudinally thereof and reinforces the roadway against the tendency for longitudinal cracking. A longitudinal section, that is, a cross section through the reinforcing elements, has a greater cross sectional area of metal than a transverse section, that is, a section across through the longitudinal tie wires. The elements 2 and 3 extend transversely of the length of the fabric, and transversely of the roadway in which they are to be used, being placed in alternating relation to each other, with their inner end portions overlapped, as shown in said figures. This overlapping, as will be readily seen, approximately doubles the cross-sectional area of the reinforcing area at the central portion of the fabric, where this metal is most needed. If it is not desired that the middle of the roadway have a greater reinforcement than the side portions thereof, the overlapping of the transverse elements, as shown in Fig. 2, or the use of extra reinforcing elements along the middle of the fabric, as shown in Fig. 3, may be dispensed with, and the transverse reinforcing elements may extend completely across the roadway so that their will be the same weight of metal at the edges as at the center. The tie or stay wires 4 may be united to the elements 2 and 3 by welding, but are preferably tied thereto as indicated at 5 in any suitable manner known in the art of making wire fabrics. I prefer to use ties rather than welded connection, since this enables me to use tie wires of a much smaller size and at a section so much smaller than the section of the elements 2 and 3 as to make it practically impossible to make a weld between them.

In the form of my invention shown in Fig. 3, there is a main series of transversely extending reinforcing elements 6; and at the central portion of the fabric an auxiliary

reinforcing element 7 is placed between each pair of elements 6, this giving the same increased cross-sectional area at the central portion of the fabric as in the form first described. It may be advisable to provide for the manufacture of both forms of the fabric, since in making the form shown in Fig. 3 it is possible to use for the reinforcing element 7 some of the ends cut from the elements 2 and 3 of the form first described, and thus economize in the use of metal. A greater reinforcement for the middle of the road may also be had by using two strips of fabric which have the same weight of metal throughout their width, and overlapping such strips of fabric along the middle of the roadway.

As shown in Fig. 1, the fabric can be formed into a roll by rolling in a direction at right angles to the length of the reinforcing elements, thus making it unnecessary to bend such elements in rolling. In laying the fabric, the roll or spindle upon which it is wound can be placed transversely 25 of the roadway with its ends resting upon the forms 8, and the fabric can then be unwound in the direction of the length of the roadway. This enables a considerable length of fabric to be laid in continuous stretch 30 without cutting, and greatly reduces the number of overlaps required.

The advantages of my invention will be readily apparent from the foregoing, since it provides a fabric for the purpose described 35 which can be manufactured and laid much more conveniently and economically than was possible with fabrics heretofore in use.

I claim:

1. A concrete roadway reinforcing fabric,

comprising comparatively heavy transverse 40 reinforcing elements adapted to be laid transversely of the roadway and comparatively light longitudinal flexible tie wires, substantially as described.

2. A concrete roadway reinforcing fabric 45 adapted to be laid lengthwise longitudinally of a roadway and having a considerably greater cross-sectional area along a longitudinal section than along a transverse section, substantially as described. 50

3. A concrete roadway having reinforcing fabric embedded therein, said fabric being laid lengthwise longitudinally of the roadway and having comparatively heavy trans- 55 verse reinforcing elements and compara- tively light longitudinal tie wires, substan- tially as described.

4. A concrete roadway having reinforcing fabric embedded therein, said fabric being laid lengthwise longitudinally of the road- 60 way and having comparatively heavy trans- verse reinforcing elements and compara- tively light longitudinal tie wires, said roadway having a greater number of reinforcing elements along its middle portion than at its 65 side portions, substantially as described.

5. A concrete roadway having reinforcing fabric embedded therein having transverse reinforcing elements and longitudinal tie wires, said roadway having the reinforcing 70 elements extending from each side of the roadway past the center thereof so as to form a considerable over-lap along the middle portion of the roadway, substantially as described. 75

In testimony whereof I have hereunto set my hand.

EDWARD L. BENEDICT.
